UNITED STATES PATENT OFFICE.

HALVOR O. EIANE, OF DETROIT HARBOR, WISCONSIN.

SUBMARINE GUN.

1,312,897.

Specification of Letters Patent. Patented Aug. 12, 1919.

Application filed May 24, 1916. Serial No. 99,672.

To all whom it may concern:

Be it known that I, HALVOR OLSEN EIANE, a citizen of the United States, residing at Detroit Harbor, in the county of Door and 5 State of Wisconsin, have invented a new and useful Submarine Gun, of which the following is a specification.

My invention relates to improvements in submarine guns, in which the chief objects 10 are, first, to mount the gun in the interior of a submarine vessel; second to provide the gun with such means that it can be fired, as well when the submarine vessel is slightly submerged, as when on the surface of the 15 water.

I attain these objects by the use of a gun, having a novel mounting, and operating mechanism, hereinafter more fully described, and claimed, having reference to 20 the accompanying drawings, in which Figure "1," represents a side view of the gun in its mounting, and with its operating mechanism. Fig. "2," represents a sectional side view of the gun, showing how shell and 25 powder charge are held in place in the chamber of the gun. Fig. "3," is a rear view of the recoil cylinders, with segmental runners. Fig. "4," is a sectional rear view of the pivotal mounting for the muzzle end of 30 the gun. Fig. "5," is a side view of the holder of the powder charge. Fig. "6," is a side view of the loading mechanism for the 35 gun. Fig. "7," is a top view of a submarine vessel, showing location of the gun. Fig. "1," in Fig. "1," is the gun barrel. "2," are the recoil cylinders. "3," are the segmental runners. "4," is the circular track. "5," are the rollers, which are placed between the 40 segmental runners "3," and the circular track "4." The globe-headed sleeve "6," is movably fitted into an aperture "7," with globular cavity, which constitutes the pivotal mounting on the muzzle end of the gun "1." When the gun is ready to be fired, the 45 crank handle "8," is given a complete turn, this movement also turns the cam "9," which first disengages the pawl "10," and then raises the lever "11," which in turn moves the reversing valve "12," into position which 50 starts the engine "13," to revolve in the right direction; the worm "14," which is secured on the crank shaft "15," turns the worm wheel "16," which is secured on the shaft "17." The shaft "17," passes through the 55 bearing "18," and the stuffing box "19," and carries on its upper end a bevel gear "20,"

which engages the bevel toothed sector "21," which is an integral part of the closure "22"; and at the same time the closure "22," starts to open, the worm "23," turns the worm wheel "24," which is connected to the valve "25," and causes a simultaneous opening of said valve, and said closure; and a strong flow of compressed air or gas, from a suitable reservoir (not shown) passes through the pipe line "26," and up through the passage "27," in the wall of the aperture "7," (shown in Fig. "4,") and into the circular groove "28," in the globe-headed sleeve "6," where the air flows around the gun barrel "1," and up through the narrow space between the gun barrel "1," and the inside wall of the globe-headed sleeve "6," forming a protective wall of fast flowing air, against inrush of water into the bore of the gun barrel "1." There will also be an additional set similar to "23," "24," "25," and "26," leading to the passage "29," and into the circular groove "30," from which the air flows into the passages "31," (shown in Fig. "2,") 80 and out through the bore of the gun barrel "1"; also for the purpose of keeping water out of the bore of the gun barrel "1." When the closure "22," has about reached its full opening, the arm "32," on the worm wheel "24," closes an electric circuit (not shown) 85 which fires the gun. As the gun barrel "1," recoils, the air passages "31," will automatically be closed, and the slotted end of the lever "33" which is connected to the gun barrel "1," will on its return movement to normal position, through the spring actuated pawl "10," engage the lever "11," which is connected to the reversing valve "12," and thus reverse the engine "13," which closes 90 the closure "22," and shuts off the air valve "25." There will be two sets like "14," "15," "16," "17," "18," "19," "20," and "21." The two worms "14," and "23," will preferably be double threaded in order to increase the 95 speed of the worm wheels "16," and "24." A suitable indicator may be connected to the shaft "17," so as to indicate the position of the closure "22." When the gun is to be loaded, the following operations take place: 100 The lever "34," which is connected by reach rod and rocker arms, to the reversing valve "35," on the engine "36," is worked, which starts the engine to revolve in the right direction, and the rotary movements of the 105 crank shaft "37," are transmitted through the worm "38," engaging the worm wheel

"39," which is secured on the shaft "40"; the shaft "40" passes through the bearing "41," and is connected by the universal joint "42," to the threaded screw "43," which engages 5 the threaded eye bolt "44"; the latter being turnably fitted into the rear end of the runners "3," and as there will be two sets like "38," "39," "40," "41," "42," "43," and "44," it will be seen that the gun "1," can be 10 moved by its rear end support to the limit of its travel toward the door "45." After the door "45," has been opened, the hinged loading spoon "46," is raised into position, and a shell placed on the spoon, from which point 15 the loading arm "47," raises the shell into the chamber of the gun "1." The shell is then rested on two spring moved check pawls, located on each side of the loading spoon "46," shown by dotted lines "48." 20 The loading arm "47," is then brought back to its starting point, and the extension ram "49," swung by hand under the shell, which is then forced into its place in the chamber of the gun "1"; and an expansion ring "50," 25 on the shell "51," expands into a groove "52," (shown in Fig. "2,") which holds the shell "51," in place. The powder charge, which preferably will be kept in a suitable canvas bag of the required size, will be loaded 30 into the chamber of the gun "1," in the same manner as the shell. An iron bar "53," provided at its lower end with a flange "54," and at its upper end with expansion barbs "55," will be placed in the center of the 35 powder bag, and the expansion barbs "55," expand into a recess "56," on the rear end of the shell "51," thus holding the powder charge in place in the chamber of the gun "1." The loading arm "47," will be operated 40 by compressed air moving a piston in a hinged cylinder, and controlled by a hand moved valve. The engines "13," and "36," will also be operated by compressed air. As the gun "1," will be placed in a water tight 45 compartment, in order to better insure the safety of the vessel, which carries said gun, it is therefore necessary to provide means for ascertaining the angle of the gun, on the outside of said compartment, and for this 50 means, the forked connecting rod "57," transmits the angular movements of the gun "1," from the globe-headed sleeve "6," to the crank lever "58," which is connected to the pointer "59," from which reading may 55 be taken on the graduated sector "60." The connecting rod "57," also keeps the globe headed sleeve "6," from turning in the aperture "7." The gun "1," will be provided with a suitable counter weight, (not shown) 60 and attached to the screw "61" which is threaded opposite to the screw "43," object being to keep the submarine vessel on an even keel. If it should be desired to remove the load from the gun without firing, the following means may be employed. By un-

screwing the flange "54," the powder may be removed; and by providing four or more longitudinal grooves in the chamber of the gun "1," slightly deeper than the groove "52," through which wedges may be inserted, and the expansion ring "50," disengaged from the groove "52," and the shell removed. The gun will be mounted in the middle of a submarine vessel, and centrally between two hydroplanes "62," and "62," of 75 sufficient strength to bear the strain produced by the recoil, when the gun is fired. The submarine vessel which carries the gun will be provided with suitable trimming tanks, fore and aft, as well as on both sides 80 for the purpose of keeping the submarine vessel on an even keel, and also tanks for compensating weight discharged by the gun. The gun may be mounted single as shown in the accompanying drawings, or in pair side 85 by side. I do not wish to be understood to limit my invention to the exact description, and drawings, as herein given, as many changes can be made without departing from the principles involved. 90

Having thus described my invention, what I claim as new and desire to secure by Letters Patent is—

1. A submarine gun having its muzzle end pivotally mounted, and its breech end supported through suitable recoil cylinders provided with segmental runners and movable to angular positions on circular guide tracks having their center of circle in the pivotal mounting of the muzzle end of said gun. 95

2. A submarine gun having its muzzle end pivotally mounted, and its breech end supported through suitable recoil cylinders with segmental runners adapted for angular movements on circular tracks, said pivotal mounting comprising a globe-headed sleeve, with its globe-end movably fitted into an aperture with a globular cavity on a submarine vessel's upper portion, and said gun capable of recoil movements through said globe-headed sleeve and recoil cylinders. 105

3. A submarine gun having its muzzle end pivotally mounted in an aperture of a submarine vessel, and its breech end supported through suitable recoil cylinders, said gun capable of recoil movements in its mounting, and movable by its rear support to angular positions on suitable circular tracks, and said aperture provided with a hinged watertight closure, and said closure provided with a 115 pair of toothed sectors, and means for opening and closing said closure through suitable transmission gears engaging said toothed sectors from a source of power in the interior of said submarine vessel. 120

4. A submarine gun having its muzzle end pivotally mounted in an aperture of a submarine vessel, and its rear end supported through suitable recoil cylinders, said gun being capable of recoil movements in its 130

- mounting, and movable by its rear support to angular positions on suitable circular tracks, a hinged watertight closure over said aperture connected by suitable transmission gears to a source of power, and said source of power controlled by hand for the opening of said closure, and automatic means for controlling the closing operation of said closure.
- 5 5. A submarine gun having its muzzle end pivotally mounted in a suitable aperture of a submarine vessel, and its rear supported through suitable recoil cylinders, said gun being capable of recoil movements in its mounting, and movable by its rear support to angular positions on suitable circular tracks, a watertight closure over said aperture, means for operating said closure, and means for imparting angular movements to
- 10 20 said gun, said means consisting of a pair of threaded screws engaging threaded eye-bolts turnably fitted into the rear ends of segmen-
- tal runners extending from the recoil cylinders of said gun, and means for controlling said angular movements at the will of the operator.
6. A submarine gun of the type herein described, having a closure for its muzzle, and a double set of air blowing means which provide a strong stream of air through the bore, and around the muzzle of said gun, capable of keeping the water out from the bore of said gun, and automatic means for simultaneously turning on, and shutting off the air supply with the opening and closing of said closure over the muzzle of said gun.
- In testimony hereof I have hereunto affixed my signature in the presence of two subscribing witnesses.

HALVOR O. ELANE.
